UNITED STATES PATENT OFFICE.

HENRY H. ROELOFS, OF ELKINS PARK, PENNSYLVANIA.

DESIGN FOR A SOFT FELT HAT.

No. 39,680.

Specification for Design.

Patented Dec. 1, 1908.

Application filed August 19, 1908. Serial No. 449,383. Term of patent 7 years.

To all whom it may concern.

Be it known that I, HENRY H. ROELOFS, a citizen of the United States, residing in Elkins Park, Pennsylvania, have invented a certain new, original, and ornamental Design for Soft Felt Hats, of which the following is a specification, reference being had to the accompanying drawing, forming part thereof, in which—

Figure 1, is a perspective view of the front

of the hat; Fig. 2, is a side view; Fig. 3, is a front view; and Fig. 4, is a perspective view of the back of the hat.

I claim:—

The ornamental design for a soft felt hat, as shown.

HENRY H. ROELOFS.
